UNITED STATES PATENT OFFICE.

JAMES L. WRAY, OF ROCK ISLAND, ILLINOIS.

PNEUMATIC PUMP.

Application filed May 9, 1921. Serial No. 467,873.

To all whom it may concern:

Be it known that I, JAMES L. WRAY, a citizen of the United States, residing at Rock Island, in the county of Rock Island and State of Illinois, have invented a new and useful Pneumatic Pump, of which the following is a specification.

This invention relates to pneumatic pumps designed primarily for hoisting water, oil or other fluids, one of its objects being to provide a device of this character which does not require the use of springs or stuffing boxes, needle valves, or other parts likely to cause trouble and interfere with the proper operation of the mechanism.

Another object is to provide mechanism of this character which, when coupled with a supply of air under pressure, will operate intermittently to elevate the liquid admitted to the apparatus.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

35 In said drawings

Figure 1 is a longitudinal section through the upper portion of the apparatus constituting the present invention.

Figure 2 is a longitudinal section through the lower portion thereof.

Figure 3 is a section through the casing of the pressure controlling valve.

Referring to the figures by characters of reference 1 designates an elongated cylindrical pump casing adapted to be submerged and provided, at its lower end, with a head 2 the upper end of which constitutes a valve seat 3 while the lower portion thereof constitutes a guard or cage as shown at 4. In 45 this head are provided guides 5 for the stem 6 of a valve 7. This valve is normally mounted on the seat 3 so as to prevent liquid from flowing downwardly out of the casing 1 after it has once entered the casing.

50 The upper end of the casing 1 is closed

by a head 8 having projections 9 thereon for engagement by a suitable wrench or other tool whereby the head can be readily screwed into or out of position. Extending downwardly from this head 8 is a tubular projection 10 having an inlet port 11 in the wall thereof and an outlet port or vent 12 extending through the head 8. A valve 13 is slidably mounted within the extension 10 and is connected to a stem 14 slidable in the head 8 and adapted to be operated by any suitable means indicated generally at 15. This valve 13 is normally in position to close the vent 12 but by forcing it downwardly past the inlet port 11 liquid can be admitted to the casing 1 through the head 8. This actuation of the valve 13 is only effected in emergencies when the air pressure hereinafter referred to is not sufficient to cause the complete operation of the mechanism and it is desired to reset the parts without taking the mechanism apart after withdrawing it from the well or other body of liquid.

Extending through the top head 8 is a liquid outlet pipe 15' to which is connected a supply pipe 16 which hangs from the head 8 and within the casing 1. This supply pipe is provided at its lower end and close to the valve 7, with a casing 17 having an inlet 18 at its lower end. A check valve 19 is mounted in this casing and is adapted normally to close the inlet 18 so as to hold the pipes 16 and 15' primed.

Arranged within the upper portion of the casing 1 is a valve casing 20 open at its ends and provided, at an intermediate point, with an annular series of outlets 21. Opening into this casing 20 between the ports 21 and the lower end of the casing is a passage 22 adapted to receive air under pressure from a pipe 23 which opens through the head 8 of the casing and extends from a suitable storage tank or the like having a supply of air under pressure. An exhaust passage 24 opens into the casing 20 between the ports 21 and the upper end of the casing, this passage preferably communicating with the casing 20 through a cluster of ports indicated at 25. The passage 24 is adapted to discharge through the head 8 into a suitable exhaust pipe provided therefor and which has been indicated by dotted lines at 26 in Figure 3.

Slidably mounted within the casing 20

is a valve 27 having heads 28 and 29 at the ends thereof and an intermediate packing ring or flange 30. The stem of the valve projects upwardly as indicated at 31 and is pivotally attached to a lever 32. This lever is pivotally mounted, at one end, upon the casing 20, as shown at 33, while its other end projects into the forked upper end of an elongated weight 34. This forked end is pivotally connected, above the lever 32, to a main lever 35, as indicated at 36, the said lever 35 being fulcrumed between its ends in a bracket 37 extending downwardly from the head 8. The other end of the main lever 35 is pivotally attached to a block 38 from which projects a lug 39. A rod 40 extends downward from this block and is secured to a finger 41 radiating from a collar 42 secured on a sleeve 43 which is slidably mounted on the pipe 16. A float 44 is carried by this sleeve.

A collar 45 is secured to the upper portion of the pipe 16 and normally supports a float 46 which is slidable on the pipe 16 and has an upwardly projecting tripping finger 47. A hanger 48 extends downwardly from the head 8 and has a latch 49 pivoted thereon and normally engaging the lug 39 so as to hold the levers 35 and 32 and the valve 27 normally positioned as shown in Figure 1 with the exhaust passage 24 out of communication with the ports 21. A link 50 connects the latch 49 to one end of a lever 51 which is fulcrumed on the hanger 48 and projects into the path of the finger 47.

When the parts are thus located the valve 27 will be secured in the position shown in the drawings.

Assuming that the ports 21 are in communication with the exhaust passage 24 and that the piston head 28 is closing the outlet of the passage 22, then the liquid in which the casing 1 is submerged, seeking its level, will rise through the head 2, lifting the valve 27 from its seat. As the liquid continues to rise it will pass above the float 44 because this float is held down by the latch 49 engaging the lug 39. As the level of the liquid continues to rise it will come against and elevate the float 46 causing the finger 47 ultimately to move against the lever 51. This will cause the latch 49 to become disengaged from the lug 39 with the result that the released float 44 will promptly move upward a limited distance, carrying with it the rod 40. This movement will be accelerated by the weight 34 and motion will be transmitted through lever 32 to the valve 27 which will be shifted promptly so as to close communication between the ports 21 and the exhaust passage 24 and open communication between the passage 22 and said ports. Consequently air under pressure will immediately rush into the casing 1 and press the liquid from said casing and upwardly

through the pipe 16 to pipe 15. This action will continue until the float 44 moves downwardly with the level of the liquid so as to pull on the rod 40 and reset the parts 39 and 49 and at the same time shift the valve 28 to place the ports 21 in communication with the exhaust passage 24 and to close the outlet of the pressure passage 22. Thus the operation just described will be repeated.

What is claimed is:—

1. Apparatus of the class described including a casing having a valved liquid inlet at its lower end, an outlet pipe extending from the casing and having a valved inlet at its lower end and adjacent the bottom of the casing, a valve casing having a pressure inlet and an exhaust, said casing being provided with a port in communication with the interior of the casing of the apparatus, a valve slideable within the valve casing and shiftable to place said port in communication either with the pressure inlet or the exhaust, means for locking the valve in exhaust position, a lower float within the casing of the apparatus and normally held depressed by said locking means, an upper float shiftable with the rising level of liquid within the casing of the apparatus to release the valve and the lower float, said lower float when released being shifted upward automatically to move the shifted valve and place the pressure inlet in communication with the port in the valve casing, and means operated by the downward movement of the lower float with the level of the liquid in the casing of the apparatus for returning the valve and the locking means to normal positions.

2. The combination with a main casing having a valved liquid inlet and an outlet pipe extending into the casing and having a check valve, of a valve casing within the main casing and having a pressure inlet and an exhaust outlet, superposed independently operating floats within the main casing and guided by the outlet pipe, means for holding the valve in the valve casing normally in one position to permit the exhaust of air from the apparatus and for holding one of the floats against movement, and means operated by the rise of the other float for releasing the valve and the held float to shift the valve and place the pressure inlet in communication with the interior of the apparatus.

3. The combination with a main casing having a valved liquid inlet, of an outlet pipe within the casing having a check valve, superposed independently movable floats upon said pipe, a valve casing within the main casing and having a port communicating therewith, a pressure passage opening into said casing and an exhaust passage in communication with said valve casing, a valve within the valve casing, means for holding the valve normally positioned with the port in communication with the exhaust

passage, means operated by the rise of one of the floats for releasing the valve, and means operated by the other float when the valve is released for shifting the valve to close the exhaust passage and place the pressure passage in communication with the port.

In testimony that I claim the foregoing as my own, I have hereto affixed my signature in the presence of two witnesses.

JAMES L. WRAY.
